UNITED STATES PATENT OFFICE.

WILLIAM H. SILVER, OF NEW YORK, N. Y., ASSIGNOR TO SILVER & COMPANY, OF NEW YORK, N. Y., A CORPORATION OF NEW YORK.

DESIGN FOR AN OIL-STOVE-BURNER DRUM.

SPECIFICATION forming part of Design No. 36,441, dated July 14, 1903.

Application filed March 27, 1903. Serial No. 149,852. Term of patent 7 years.

To all whom it may concern:

Be it known that I, WILLIAM H. SILVER, a citizen of the United States of America, and a resident of the borough of Brooklyn, New York city, in the State of New York, have invented a new, original, and ornamental Design for an Oil-Stove-Burner Drum, of which the following is a specification.

The present design consists in the shape, configuration, and ornamentation of the drum represented by the accompanying drawing, which is a side elevation of an oil-stove-burner drum, showing my new and original design.

I claim as my invention and desire to patent under this specification—

The new and ornamental design for an oil-stove-burner drum, substantially as shown.

In testimony whereof I have signed my name to this specification in the presence of two subscribing witnesses.

WILLIAM H. SILVER. [L. S.]
